UNITED STATES PATENT OFFICE.

VICTOR GELPK, OF LUZERN, SWITZERLAND, ASSIGNOR TO DEUTSCHE EVAPORATOR-
AKTIEN-GESELLSCHAFT, OF BERLIN-WILMERSDOEFF, GERMANY.

KILN WITH HEATING CHAMBERS AND COOLING CHAMBERS.

1,426,287.

Specification of Letters Patent. Patented Aug. 15, 1922.

Application filed March 16, 1921. Serial No. 452,827.

To all whom it may concern:

Be it known that I, VICTOR GELPK, a citizen of the Helvetic Confederation, and resident of Luzern, Reckenbühlstr. 2, Switzerland, have invented a certain new and useful Improved Kiln with Heating Chambers and Cooling Chambers, of which the following is a specification.

This invention relates to a kiln having a heating space or chamber and a cooling-space or chamber or a plurality of such ones. The gist of the invention resides in the feature that the cooling-chamber is connected with a yielding member, the object of which is to prevent that the expansion or extension of the heating-chamber due to the heating is transmitted to the cooling-chamber in a manner likely to do damage to this chamber.

It is, already known with tubes, it is true, to compensate elongations due to heat by means of compensating-pipes or the like inserted into the tubing at suitable places, but such pipes are applicable only in connection with tubes or pipes or circular section. They are provided with circular rings at their flanges and are merely adapted to compensate a uniform extension taking place in the longitudinal axis of the respective tubes or pipes.

In contradistinction to this known contrivance, the compensating-means employed in connection with the improved kiln is apt for use in connection with any desired profile, especially such as that of a chamber of the kind in question, and it allows of compensating extensions in the axial direction, also if they are different at different parts of the circumference of the chamber. They may, for instance, be greater in the upper part of the chamber than in the lower part. But also movements of different magnitude in transverse directions are effectively compensated by the novel member in question, as will appear from the following.

In order to make my invention more clear, I refer to the accompanying drawing, in which similar letters denote similar parts throughout the several views, and in which, Figure 1 is a longitudinal section through a kiln, as well as through the heating-chamber and the cooling-chamber. Figure 2 is a transverse section in line *a*—*b* of Figure 1. Figure 3 shows a detail of Figure 1 on a larger scale.

1 is the kiln proper, or its masonry respec-

tively, which contains the heating-chamber 2. 4 is the cooling-chamber, and 3 is a slide-valve casing having a slide valve 22 arranged between the chambers 2 and 4. By this slide-valve 22 the interiors of the chambers 2 and 4 are divided from one another. The slide-valve is combined with a yielding member 5 which in its simplest form of construction, as shown in the drawing, consists of two rectangular thin sheets of metal 6 having large openings cut according to the profile of the chambers. These plates 6 are gas-tight and are connected with each other at 7, which may be effected by riveting, screwing, welding or the like, and between said plates is an interstice 8 which in axial direction is a little larger than necessary to make up for the increase in length of the chamber 1 when getting from the cold state into the heating one. The plates 6 have central openings corresponding in width to the clear width of the chamber 4, as well as to that of the slide-valve 3, and they are connected with these parts (3 and 4) also gas-tight by screws 9, as shown in Figures 1 and 3.

In the enlarged illustration Figure 3 the construction is slightly different from Figure 1, because the sheet-metal plates 10 which form the compensating-member are completely flat and connected at their rims by ledges 11 (see also Figure 2) and bolts 7. In all other respects the construction is exactly the same as that already described.

The yielding member or compensating member 6—6, or 10—10 respectively, need not be arranged between the slide-valve casing and the cooling-chamber, but may be arranged also between the slide-valve and the heating-chamber, or it may be arranged at the rear end of the cooling-chamber; and where instead of only one cooling-chamber two or more are made use of, there also more than one compensating-member may be provided.

The cooling-chamber has at and below its bottom ribs 12 which are adapted to roll upon rollers 13 supported by the base or socle 14. The chamber 4 with its contents is thus carried by said base or socle 14. The contents consists, in the example shown, of a truck 15 loaded with certain articles of manufacture which are first to be annealed and then to be cooled.

16 is a horizontal plate which extends

through the compensating-member and is affixed, in the example shown, by screws 17 to the slide-valve casing 3. At the opposite rim of said plate 16 are holes receiving the heads of pins 19. The diameter of the pin-heads is somewhat smaller than that of the plate-holes, there being left some dead play 18 (Fig. 3) which determines the extent of the relative motion between the parts 3 and 4.

It appears from what has been described and shown that the longitudinal movements of the heating-chamber and the slide-valve casing is compensated by the compensating-member, in that the one plate approaches the other as much as allowed by the dead play 18. Then the cooling-chamber is displaced and moved upon the rollers 13. These may be dispensed with, if also the plate 16 is dispensed with, when the whole extent of the elongation of the heating-chamber is taken up by the member 6—6 or 10—10.

The extent of the elongation may be different in different parts of the heating-chamber; it may be greater at the top 20 than at the bottom 21. Also movement or expansion in transverse direction may be compensated and rendered ineffective by the member in question. Without this latter, any one, or several, of the flanges located at or between the chambers are exposed to the risk of being broken off.

If the compensating-member is to compensate only such small extensions as may occur after the heating operation has been finished, the plate 16 may be arranged in the manner described and shown when the dead-play 18 will determine the extent of motion not to be transmitted to the cooling-chamber, whereas any surplus makes this chamber move upon the rollers 13. A movement or movements of the same extent may

arise on the chamber or parts concerned cooling down when the direction of motion 45 will be, of course, the reverse of what it has previously been.

The arrangement of the plate 16 offers, besides, the further advantage that the transmission of the forces arising from the heating-chamber bottom to the cooling-chamber bottom is effected without any comparatively strong bending-stress, in contradistinction to connections by flange-screws which entail considerable bending stresses. 55

Having now described my invention, what I desire to secure by a Patent of the United States is:

1. A kiln, comprising, in combination, a furnace, a heating-chamber, a cooling-chamber, and a compensating-member arranged between said chambers; said member consisting of two sheet-metal plates arranged in an appropriate distance one from the other, and gas-tight connections between 65 said plates, as well as between them and the structure-components with which they are connected.

2. A kiln, comprising, in combination, a furnace, a heating-chamber, a cooling-chamber, a compensating-member between said chambers, a plate firmly connected with one side of said member, a hole in the opposite end of said plate, a stud extending through said hole into a part connected with the 75 other side of the said member, the relative diameter of the said hole and said stud being such that some dead play is left, for the purpose set forth.

In testimony whereof I affix signature in 80 the presence of two witnesses.

VICTOR GELPK.
